UNITED STATES PATENT OFFICE.

LOUIS J. WILLENBURG, OF SPRINGVALLEY, OHIO.

DESIGN FOR A BARREL-TRUCK.

SPECIFICATION forming part of Design No. 85,034, dated September 3, 1901.

Application filed July 8, 1901. Serial No. 67,548. Term of patent 7 years.

To all whom it may concern:

Be it known that I, LOUIS J. WILLENBURG, a citizen of the United States, residing at Springvalley, in the county of Greene and State of Ohio, have invented and produced a certain new and useful Design for a Barrel-Truck; and I do declare the following to be a full, clear, and exact description of the invention, such as will enable others skilled in the art to which it appertains to make and use the same, reference being had to the accompanying drawing, and to the letters of reference marked thereon, which forms a part of this specification.

The drawing represents a perspective view of a barrel-truck, showing my new design.

As shown in said drawing, the leading or material features of my new design consist of two parallel bars A, the surfaces of which incline inwardly and the four ends B of which

are projected downwardly to provide bearings for the journals of four rollers C. Connected to the ends B of said bars A are two parallel united bars D, which extend at right angles to the planes of the bars A and terminate in rounded hand-grips E. The ends of the bars D extend outwardly to the ends of the bars A and are united thereto and receive the journals of the rollers C. 25

Having described my invention, what I claim as new, and desire to secure by Letters Patent, is—

The design for a barrel-truck, as herein shown and described.

In testimony whereof I affix my signature in presence of two witnesses.

LOUIS J. WILLENBURG.
